Primary Examiner — Eric Goodman*Assistant Examiner* — Ryan Harvey(74) *Attorney, Agent, or Firm* — Locke Lord LLP(57) **CLAIM**

The ornamental design for a four wheel all-terrain vehicle, as shown and described.

DESCRIPTION

FIG. 1 is a front-left perspective view of the four wheel all-terrain vehicle showing the new design thereof;

FIG. 2 is a front-right perspective view thereof;

FIG. 3 is a left side view thereof;

FIG. 4 is a right side view thereof;

FIG. 5 is a top view thereof;

FIG. 6 is a front view thereof;

FIG. 7 is a rear view thereof;

FIG. 8 is a rear-left perspective view thereof; and,

FIG. 9 is a rear-right perspective view thereof.

The broken lines showing portions of the four wheel all-terrain vehicle are included for the purpose of illustrating environmental structure and form no part of the claimed design.
